The ornamental design for a mic block, as shown and described.

DESCRIPTION

FIG. 1 is a front top right perspective view of the mic block;
FIG. 2 is a rear top left perspective view thereof;
FIG. 3 is a front elevational view thereof;
FIG. 4 is a left elevation view thereof;
FIG. 5 is a right elevation view thereof;
FIG. 6 is a rear elevation view thereof;
FIG. 7 is a top plan view thereof;
FIG. 8 is a bottom plan view thereof;
FIG. 9 is a perspective view of the mic block inserted into the mic port of a mobile device during use; and,
FIG. 10 is an exploded view thereof.

The broken lines shown in the drawings are included to illustrate environment portions of the mic block that form no part of the claimed design.

1 Claim, 4 Drawing Sheets
